PACKING BOX FOR A WRITING INSTRUMENT
AND REPLACEMENT CARTRIDGES THEREFOR
OR SIMILAR ARTICLES

Julius M. Kahn, Englewood, N. J., assignor to David Kahn, Inc., Hudson County, N. J., a corporation of New Jersey

Application September 27, 1956, Serial No. 43,113

Term of patent 14 years

(Cl. D58—13)

FIG. 3

Fig. 1 is a perspective view of a packing box for a writing instrument and replacement cartridges therefor, or similar articles, showing my new design;

Fig. 2 is a top plan view of the box;

Fig. 3 is a bottom plan view of the box; and

Fig. 4 is a section taken on line 4—4 of Fig. 2.

I claim:

The ornamental design for a packing box for a writing instrument and replacement cartridges therefor or similar articles, substantially as shown.
